UNITED STATES PATENT OFFICE.

FRANK H. SIEH AND FREDERICK J. LOWE, OF MINNEAPOLIS, MINNESOTA.

MAIL-BOX.

935,934.

Specification of Letters Patent.

Patented Oct. 5, 1909.

Application filed June 24, 1909. Serial No. 504,114.

To all whom it may concern:

Be it known that we, FRANK H. SIEH and FREDERICK J. LOWE, citizens of the United States, residing at Minneapolis, in the county 5 of Hennepin, State of Minnesota, have invented a new and useful Mail-Box, of which the following is a specification.

This invention relates to mail boxes for use upon the doors of residences, offices, etc., 10 and its object is to provide means whereby a signal will be sounded whenever the closure of the mail-receiving slot in the box is opened, or whenever the paper-holding clip upon the bottom of the box is depressed.

Another object is to provide novel means 15 for closing an electric circuit when the paper-holding clip is depressed, said means being disposed to be shifted out of engagement with its contact after a paper has been placed 20 in position above the clip.

With these and other objects in view the invention consists of certain novel details of construction and combinations of parts hereinafter more fully described and pointed out 25 in the claims.

In the accompanying drawings the preferred form of the invention has been shown.

In said drawings:—Figure 1 is a central vertical section through a mail box embodying the present improvements, the various 30 parts thereof being shown in their normal positions. Fig. 2 is a perspective view of the circuit-closer used in connection with the paper clip. Fig. 3 is a perspective view 35 of the circuit closer used in connection with the closure flap of the slot in the box, the parts being shown in their normal positions.

Referring to the figures by characters of reference 1 designates a mail-box having the 40 usual opening 2 for the reception of letters and the like, this opening being provided with a closure 3, in the form of a spring-controlled flap which is held normally in closed position by the springs which have 45 been indicated at 4. A strip 5, of insulating material is secured upon the wall of the box at a point above the opening 2, and mounted on this strip is a spring strip 6, constituting a contact, said strip being electrically connected to the box 1 by means of a screw 7, which serves to hold the strip 5 and the 50 spring contact 6 in position. A non-flexible angular contact 8 is mounted on the strip 5 and laps the spring contact 6, the said spring contact being held normally pressed toward

the strip 5 by means of an arm 9, which extends from and is movable with the closure 3. A signal device, preferably in the form of an electric bell 10, may be located at any suitable point and electrically connected 60 with a battery 11, one pole of which is electrically connected with the box 1, and contact 6, while the other contact 8 is electrically connected with the battery by means of an insulated wire 12.

An opening 13 is formed in the bottom of the box 1 near the front thereof, and a spring clip 14 is secured to the box and extends under and beyond the front of the same, this clip being of the type ordinarily utilized 70 for the purpose of holding magazines, newspapers and the like upon the bottom of the box. A rod 15 is arranged adjacent the opening 13, and pivotally mounted thereon is a segmental block 16 which is held normally in contact with the clip 14 by means of a light coiled spring 17. A lug 18 extends laterally from this block and overhangs a contact 19, which is secured upon an insulating strip 20 on the bottom of the 80 box. This contact 19 is connected to the wire 12 by means of a branch wire 21, or in any other suitable manner. It is of course to be understood that the lug 18 is normally spaced from the contact 19.

It is thought that the operation of the device will be fully understood from the foregoing description when read in connection with the accompanying drawings. When the closure 2 is elevated the arm 9 moves away 90 from the spring contact 6, and said contact therefore moves against the bracket 8 and thus completes the circuit from the battery 11 to the alarm 10. This alarm will continue to be sounded as long as the closure 3 is elevated. However, when the closure is released and the springs 4 return it to its shut position, the arm 9 will again move against the contact 6 and force it away from the bracket 8, thus breaking the circuit. 100 When a paper is to be placed above the clip 14 the same is inserted under the front end of the box, and this will cause said clip to move downward a short distance, this movement being sufficient to allow the block 16 to 105 also swing downwardly and to bring its lug 18 upon the contact 19. A circuit will thus be established from the battery to the alarm, and this circuit will be maintained until the inserted paper is brought into con- 110

tact with the block 16. Said block will then be elevated so as to move the lug away from the contact 19.

It is of course to be understood that various changes may be made in the construction and arrangement of the parts without departing from the spirit or sacrificing the advantages of the invention.

What is claimed is:—

- 10 1. A mail-box including a clip coöperating with one face of the box, a spring-controlled block normally bearing upon the clip and in the path of an object inserted between the clip and box, a contact outstanding from the block, a second contact in the path thereof but normally spaced therefrom, an electric alarm, and electrical connections between said alarm and the respective contacts.
- 20 2. The combination with a mail-box, of a clip coöperating with one face of the box to retain objects there-between, a spring-controlled block movably mounted within said face and normally bearing upon the clip, normally spaced insulated contacts carried by the box and block respectively, and an electric alarm system connected to the re-

spective contacts, said movable contact being shiftable automatically against the other contact when the clip is moved away from the box.

3. The combination with a mail-box and a clip connected thereto and coöperating with one face thereof to retain an object upon said face, of a block movably mounted upon the box and projecting into the path of the inserted object, a lug outstanding from the block, a contact upon the box but insulated therefrom, and a spring for automatically shifting the block to move the lug upon the contact when the clip is depressed, said block being shiftable to break the contact by an object inserted between the clip and box, and an electric alarm system in circuit with said box and contact.

In testimony that we claim the foregoing as our own, we have hereto affixed our signatures in the presence of two witnesses.

FRANK H. SIEH.
FREDERICK J. LOWE.
